UNITED STATES PATENT OFFICE.

LE ROY W. STAUNTON, OF JACKSON HEIGHTS, NEW YORK, ASSIGNOR, BY MESNE ASSIGNMENTS, TO BRANDES LABORATORIES INC., OF NEWARK, NEW JERSEY, A CORPORATION OF NEW JERSEY.

DESIGN FOR A LOUD-SPEAKER CASING.

Application filed December 12, 1924. Serial No. 11,678. Term of patent 14 years.

To all whom it may concern:

Be it known that I, LE ROY W. STAUNTON, a citizen of the United States, residing at Jackson Heights, in the county of Queens and State of New York, have invented a new, original, and ornamental Design for a Loud-Speaker Casing, of which the following is a specification, reference being had to the accompanying drawings, forming part thereof.

Figure 1 shows a front view of my design for a cover for loud speaker casing and Fig. 2 is a side view of the loud speaker casing showing my new design.

I claim:

The ornamental design for a loud speaker casing, as shown.

LE ROY W. STAUNTON.
